UNITED STATES PATENT OFFICE

WILLIAM P. DAY, OF CLEVELAND HEIGHTS, OHIO

ROADBED CONSTRUCTION

Application filed July 15, 1929. Serial No. 378,232.

This invention relates to a roadbed construction for street or boulevard railways and the main object of the invention is to provide a roadbed construction in which water will be 5 drained away from the bases of the rails and prevented from seeping in around the rail plates.

Another object of the invention is to provide a roadbed construction of the character 10 described in which the rails are supported upon a lower layer or foundation of concrete which is provided with drain openings to permit the water to drain away from the bases of the rails.

15 A further object of the invention is to provide a roadbed construction of the character described which consists of a foundation of concrete provided with suitable drain openings for draining the water away from the 20 rail bases and in which the upper portion of the roadbed is formed of a layer of material which is readily removable to permit the rails to be replaced or repaired.

25 A further object of the invention is to provide a roadbed construction in which the bases of the rails are covered with a waterproofing material which tends to direct the water away from the rails and into suitable drain openings.

30 A still further object of the invention is to provide a roadbed construction of the character described which is provided with a centrally disposed drain or drain conduit which is disposed between the rails and from which 35 lead branch drain conduits leading to points adjacent the bases of the rails and along each side thereof.

A still further object of the invention is to provide a roadbed construction of the character described which consists of a concrete foundation on which are supported steel ties of the twin type which are so arranged as to permit the material under the rail plates to be retamped when necessary or desired and 45 in which the upper layer of road forming material is readily removable to permit access to the rails or the removal of the same.

Further and more limited objects of the invention will appear as the description proceeds and by reference to the accompanying

drawings in which Fig. 1 is a vertical sectional view disclosing the preferred form of roadbed construction; Fig. 2 is a vertical sectional view on the line 2—2 of Fig. 1; Fig. 3 is a vertical sectional view disclosing the ties 55 arranged within the trench with the rails supported thereon before the foundation is laid; and Fig. 4 is a top plan view illustrating the preferred type of tie which is to be used with this construction.

Referring now to the drawings, reference character 1 designates the bottom layer of concrete which will be referred to as the foundation. Disposed below the foundation and between the rails is a drain conduit 2 which extends longitudinally of the track and parallel therewith. Arranged at intervals about three feet apart and extending across the roadbed are trenches 3 from which lead branches 4, 4^a and 5, 5^a. The trenches 3 and 65 the branches 4, 4^a and 5, 5^a are filled with gravel, stone, cinders or other suitable material adapted to permit water to drain therethrough and into the main drain conduit 2 which is preferably formed of drain tile. 70 Supported upon the foundation 1 are ties 6 which are preferably made of steel and are of the twin type. The ties consist essentially of rail plates 7 and 8 which are connected by cross bars 9 and 10. The rail plates are provided with oppositely disposed pairs of T-shaped openings 11 and 12 which are adapted to receive tie clamps for securing the rails in place.

The ties are supported on the foundation 85 1 in such position that the cross beams 9 and 10 are partially embedded therein. The foundation is first laid with the rails supported in the position shown in Fig. 1 and the concrete is allowed to harden and set. 90 The spaces beneath the rail plates 7 and 8 are then filled with a waterproof material known as bituminous concrete which consists essentially of slag and crude asphalt in approximately the following proportions:

3 parts fine slag.

2 parts coarse slag.

1 part crude asphalt.

The rails 13 and 14 are first secured to the rail plates by means of suitable tie clamps. 100

The rail plates and the lower portions of the rails are then covered with a layer 15 of bituminous concrete and this layer of material extends between the rails as shown most clearly in Fig. 1. This material extends substantially all the way to the tops of the rails and is inclined toward the drain openings as shown most clearly in Fig. 1 so that any water which may seep in adjacent the rails will be deflected into the drain openings hereinbefore described. After this layer of material 15 has set, a second layer of concrete 16 may be applied up to about the level shown in Fig. 1. After this layer of material has set a top layer 17 of surface material is applied and may consist of asphalt or any other suitable material.

According to the preferred manner of forming the roadbed construction hereinbefore described, I first provide a trench of suitable depth and which is slightly wider than the track. I then place between the track and adjacent the bottom of the trench a main drain conduit 2 which is preferably formed of drain tile. Suitable forms are then inserted to provide the trenches 3 and the branch drain openings 4, 4^a and 5, 5^a, leading to points adjacent the opposite edges of the rails. The ties are then arranged in place and supported on suitable blocks and rails secured thereto in a manner well known to those skilled in the art. The lowermost layer or foundation 1 of concrete is then poured in a manner well known to those skilled in the art and allowed to harden and set. The spaces beneath the rail plates are then filled with bituminous asphalt and tamped in place in any suitable manner. The rail plates and the bases of the rails are then covered with a layer of bituminous concrete 15 which extends upwardly to a point near the tops of the rails. This material is allowed to set and the layer of concrete 16 is then applied as shown most clearly in Fig. 1 and allowed to harden and set. The layer of surface material 16 is then applied in any suitable manner.

By referring to the drawings, it will be seen that the branch drain conduits 4, 4^a and 5, 5^a extend through the layer of bituminous asphalt and terminate at points adjacent the rails and also adjacent the rail plates. These drain openings are preferably about three feet apart and extend along both sides of the rails. It will now be clear that any water which may seep in along the heads of the rails will strike the layer of bituminous concrete which is waterproof and be deflected into the branch drain openings 4, 4^a and 5, 5^a and drain through the trench 3 into the main drain conduit 2.

It will also be clear that the upper layers of material, including the layer of bituminous concrete, may be removed down to the foundation without disturbing the rails so as to permit removal or replacement of the

track without disturbing the foundation. With this construction I am enabled to practically prevent any water from seeping in around the bases of the rails or under the rail plates.

Various changes may be made in the manner of assembling and arranging the various parts without departing from the spirit of the invention. My invention is also not limited to any particular type of road forming material either for the foundation or for the uppermost layers. While I have in this specification used the term "concrete" it is to be understood that I do not intend by this to limit the invention to any specific mixture of material but rather to use the term generically as embracing all of that class of materials in which a suitable bonding material such as cement or asphalt is used in connection with gravel, stone or sand. It is therefore to be understood that the invention is limited only in accordance with the scope of the appended claims.

Having thus described my invention, what I claim is:—

1. In a roadbed construction for railways, a concrete foundation, a plurality of cross ties supported by said foundation, rails secured to said ties, a waterproof material covering said ties and all of the rails except the head portions thereof, a layer of concrete covering said layer of waterproof material and a layer of surface material covering said last mentioned layer of concrete.

2. In a roadbed construction for railways, a concrete foundation, a plurality of cross ties supported on said foundation, rails secured to said ties, a waterproof material covering said ties and all of the rails except the head portions thereof, road forming material covering said layer of waterproof material substantially up to the level of the heads of the rails, a drain conduit disposed between said rails and a plurality of branch drain conduits leading from points adjacent the rails and adapted to deliver into said drain conduit, said branch drain conduits extending through said layer of waterproof material.

3. In a roadbed construction for railways, a concrete foundation, a plurality of cross ties supported on said foundation, a layer of waterproof material covering said foundation and all of the rails except the head portions thereof, road forming material covering said layer of waterproof material, a drain conduit disposed between said rails and a plurality of branch drain conduits leading from points adjacent the rails and adapted to deliver into said first mentioned conduit, said branch drain conduits extending through said layer of waterproof material, said layer of waterproof material consisting of bituminous concrete and being disposed so as to deflect the water into said branch drain conduits.

4. A roadbed construction for street or boulevard railways comprising a concrete foundation, a plurality of ties supported on said foundation, rails secured to said ties, a 5 layer of waterproof material covering the ties and extending upwardly about the rails to a point adjacent the head portions thereof, a main drain conduit disposed between said rails, branch drain conduits leading from said 10 main drain conduit and terminating adjacent said rails, said branch drain conduits extending through said layer of waterproof material and adapted to drain water away from said rails and road forming material filling 15 the space between and along said rails. 70
5. A roadbed construction for street or boulevard railways comprising a concrete foundation, a plurality of ties supported on said foundation, rails secured to said ties, a 20 layer of bituminous concrete covering said ties and extending upwardly about said rails to a point adjacent the head portions thereof, a main drain conduit, branch drain conduits leading from said main drain conduit and 25 terminating adjacent said rails, road forming material filling the space between and along said rails, said branch drain conduits extending through said layer of bituminous concrete and terminating adjacent said rails. 75
6. A roadbed construction for street or boulevard railways comprising a concrete foundation, a plurality of steel twin ties supported on said foundation and partially embedded therein, said ties having rail plates 30 which are disposed in a plane above said foundation, a pair of rails secured to said rail plates respectively, a waterproof material covering said ties and disposed beneath said rail plates and extending upwardly about said 35 rails to a point adjacent the head portions thereof, a main drain conduit extending parallel with the track and having a plurality of branch drain conduits leading therefrom and terminating adjacent said rails, said 40 branch conduits extending through said layer of waterproof material and serving to drain water away from said rails into said main drain conduit and one or more layers of road forming material filling the space between 45 and along said rails. 80
7. A roadbed construction for street or boulevard railways as set forth in claim 6 in which said waterproof material consists of bituminous concrete. 85
8. A roadbed construction for street or boulevard railways comprising a concrete foundation, a plurality of steel ties of the twin type supported by said foundation, a pair of rails supported on said ties, said ties having 50 rail plates which are disposed in a plane above said foundation, waterproof material filling the space beneath said rail plates and a layer of waterproof material covering said ties and rail plates and extending upwardly about 55 said rails to a point adjacent the head por- 90
- tions thereof, a main drain conduit extending parallel with the track, a plurality of branch drain conduits extending laterally of the track at intervals and terminating at points adjacent said rails and along opposite sides thereof, said branch drain conduits extending through said layer of waterproof material and serving to drain water away from said rails and into said main drain conduits and one or more layers of road forming material filling the space between and along said rails. 95
- In testimony whereof, I hereunto affix my signature.
